UNITED STATES PATENT OFFICE.

THOMAS E. STUART, OF COUNCIL BLUFFS, IOWA, ASSIGNOR OF ONE-HALF TO
BENJAMIN A. SIMON, OF OMAHA, NEBRASKA.

EXHAUST NOZZLE.

Application filed June 6, 1921. Serial No. 475,563.

To all whom it may concern:

Be it known that I, THOMAS E. STUART, a citizen of the United States, residing in the city of Council Bluffs, in the county of 5 Pottawattamie and State of Iowa, have invented certain new and useful Improvements in Exhaust Nozzles, and have described the same in the following specification, illustrated by the accompanying 10 drawings.

My invention relates to that class of exhaust nozzles which are commonly used for the purpose of producing draft in the boilers of locomotive steam engines, and which individually discharge in such a boiler the exhaust steam from the engine cylinders. The main objects of my improvements are these, 15 namely: to obviate all need of applying tips to nozzles of this class; to increase the draft, or entraining effect which is obtained from a given supply of exhaust steam; to reduce the back pressure which is commonly produced by nozzles of this class, in the engine cylinders; to produce a steam jet 20 having an unchanging peripheral form throughout its working range, and having the highest velocity which is attainable with a given back pressure; and to reduce the violence and unsteadiness of draft which are 25 due to intermittency in the flow of exhaust steam coming from the cylinders in puffs. To accomplish these objects I incorporate in my improved nozzle as integral parts thereof, a flaring, or uniformly expanding, 30 tubular shell, a peripheral flange at the base of the nozzle, and a plurality of straight, longitudinal internal corrugations of the shell which extend from near the base to the top of the nozzle with gradually in- 35 creasing cross section.

In said drawings, illustrating the best manner in which I have contemplated applying the principles of the invention, Fig. 1 is a plan view of an exhaust nozzle which 40 is constructed in accordance with these principles. Fig. 2 is an axial section on the section line 2—2 of Fig. 1. Fig. 3 is a plan of my improved nozzle in a modified form. Fig. 4 is an axial section on the section line 45 4—4 of Fig. 3. Fig. 5 is a front elevation partly in vertical cross section and partly diagrammatic, showing a locomotive boiler which is supplied with my improved nozzle and other appurtenances.

The shell of the nozzle, in its preferred 55 form, is denoted in Figures 1 and 2 by the numeral 6. It is an iron casting and has at the base, which is its receiving end, the outstanding flange 7, which is adapted to be united imperviously in a flange joint with 60 the flange 8 similarly encircling the top of the steam passage 9 of the saddle 10 supporting the boiler 14 as shown in Fig. 5. Its throat 11, where the section area of the 65 nozzle is least, is below the middle of the nozzle and preferably near its receiving end. From the throat upward to the top, where the opening is greatest, the nozzle is of the 70 form of a frustum of a cone, being slightly flaring in form, with its section area increasing gradually at a uniform rate. In the interior surface of the nozzle are formed a plurality of corrugations 12, the same being smooth, straight and internally projecting spaced ridges, preferably triangular in 75 cross section, which begin at or near the throat 11 and extend with gradually increasing size to the top of the nozzle. The least distance from one ridge to the next is constant at all points in their length; 80 so that the unbroken strip of surface between them is of uniform width from end to end. In the aggregate, however, the increasing section area of these ribs is insufficient to prevent the effective internal 85 section area of the nozzle from increasing gradually and continuously as described. The smokestack 13, fitted through the top of the boiler, has the flaring petticoat 15, which overhangs the nozzle at a suitable 90 distance above the same in the smoke box of the boiler as with other nozzles of the specified class.

In the aforementioned modified form of the invention, the parts corresponding to 95 the parts 6, 7, 11 and 12, already described, are denoted in Figures 3 and 4 by the numerals 6', 7', 11' and 12' respectively. In this modification the internal corrugations of the shell are the spaced grooves 12', which like the ridges 12, beginning at or near the throat of the nozzle and ending at the discharging orifice of the same, individually increase in section area from beginning to end.

As compared with nozzles of smooth bore, this improved nozzle, producing, as it does, a larger or increased peripheral area of

contact of the steam jet with the increased and corrugated interior surface of the nozzle, likewise and consequently produces a more extensive contact of the jet with the 5 gases which it encounters in the smoke chamber, and thereby produces a greater entraining effect. At the same time and conjointly it facilitates by its flaring form the utilization of the force of steam expansion occurring within the nozzle. Operatively the described corrugations impress 10 upon the jet their own form and arrangement and produce thereon corresponding corrugations resembling, as the case may be, 15 either grooves or ridges, and adapted to increase its entraining effectiveness.

In this operation, the expanding bore secures the highest velocity of the steam by permitting its expansion within the nozzle; 20 and the longitudinal corrugations of the bore produce an increased superficial area of the jet; while the equal spacing of the adjacent corrugations throughout their length permits them to be of uniformly increasing cross-section, and thereby prevents 25 turbulency of the steam without violating the principle of the expanding nozzle.

I claim as my invention—

1. An exhaust nozzle of the specified class, 30 having an expanding bore, and a plurality of longitudinal corrugations formed in the bore and spaced apart therein equally throughout their length.

2. An exhaust nozzle of the specified class, 35 having an expanding bore, and a plurality of longitudinal inwardly projecting and expanding ridges formed in the bore and

spaced apart with a constant least distance from each ridge to the next.

3. An exhaust nozzle, having an internal 40 circular throat, a bore expanding upward from the throat to the outlet of the nozzle in the form of a truncated cone, and a plurality of longitudinal internal corrugations formed in the bore, and equally spaced 45 apart from end to end; whereby the form of the nozzle is impressed upon the jet delivered thereby.

4. An exhaust steam nozzle, having an internal throat, a bore expanding continuously 50 at a uniform rate from the throat upward to the discharging end of the nozzle, and a plurality of straight internal corrugations which extend lengthwise of the bore from within the nozzle to said end, and 55 throughout their whole extent are of uniformly increasing size and uniformly spaced apart.

5. An exhaust steam nozzle, having an internal throat, a bore expanding at a uniform 60 rate from the throat to the outlet of the nozzle, and a plurality of inwardly projecting ridges in the expanding portion of the bore which are uniformly increasing in section area throughout their whole extent 65 and are equally spaced apart from end to end; whereby the nozzle is adapted to deliver a jet of steam having a plurality of longitudinal grooves corresponding respectively to the ridges in the nozzle. 70

Witness my signature at Omaha, Nebraska, May 6th, 1921.

THOMAS E. STUART.
